SLICE AND HEAD BOX FOR PAPER MAKING MACHINES

Filed Sept. 6, 1929

UNITED STATES PATENT OFFICE

RALPH WOOD, OF SHARON HILL, PENNSYLVANIA, ASSIGNOR TO SCOTT PAPER COMPANY, A CORPORATION OF PENNSYLVANIA

SLICE AND HEAD BOX FOR PAPER MAKING MACHINES

Application filed September 6, 1929. Serial No. 390,691.

The object of my invention is to provide means for the regulation of the weight of paper pulp stock to be fed through the slice in being delivered from the head box to the wire apron of the Fourdrinier, the regulation being such that the vertical thickness of the jet of paper stock may be varied at spaced points transversely across the width of the machine, whereby the thickness of the paper at those transverse points may be accurately adjusted and maintained to assure a substantially uniform thickness throughout the whole width of the finished web.

My invention has for a further object, a better formation and flow of the pulp stock, whereby it may travel through the slice at high speeds by reason of the absence of agitation in the jet, and by the smooth accelerating approach to the full speed through the throat of the head box and delivery from the slice.

My invention consists of the slice having a construction which enables the thickness of the jet at various spaced points transversely of the machine, to be adjusted so as to cause more or less paper stock to pass through the nozzle at said points, said improvements including special slice adjustment means to the upper lip or wall (preferably of a flexible nature) and adjusted vertically in respect to the bottom or lower wall constituting a material part of the flow nozzle of the slice to vary the paper stock flowing through the nozzle.

My invention also consists in means for simultaneously adjusting the vertical thickness of the jet throughout the entire width of the machine and more especially when associated with the spaced adjustment means above recited for adjustment of the upper lip of the slice.

My invention further consists of means for providing a gradually tapered passage or throat from the head box to the slice nozzle, whereby the stock is given an accelerating speed of flow and velocity of discharge with a minimum amount of agitation.

My invention also comprehends other features of construction which, together with those above referred to, are fully described

hereinafter and more particularly pointed out in the claims.

Referring to the drawings: Fig. 1 is a vertical section of a combined slice and head box of a paper making machine embodying my improvements; Fig. 2 is an enlarged view of a portion of Fig. 1; and Fig. 3 is a front view of the means for supporting the upper lip or wall of the slice nozzle.

The wire apron of the Fourdrinier is shown at 2, resting upon the table rolls 3 and extending about the breast roll 4.

The slice comprises the following construction: 6a represents the side or pond plates between which the nozzle 5 is arranged and forming end closure walls thereto, to insure the flow of the water and stock through the nozzle. The bottom lip or table of the slice and its nozzle is shown at 6 and extends back horizontally from the breast roll. The adjustable top lip 7 of the slice is formed of a flexible plate yieldingly connected at its rear end to a transverse channel beam 15 and is a continuation of the upper wall of the throat 8 leading to the nozzle 5. The yielding connection of the rear end of the flexible lip 7 with the channel beam 15, consists of flexible and slightly yielding sheet material 17 secured to both the lip plate and bottom of the channel beam 15, giving a slight yieldingness to the lip plate 7. This connection of the plate 7 with the channel beam permits the forward lip of the plate to assume a more or less sinuous shape under adjustment while the rear end of the plate remains substantially straight and is carried by the rigid channel beam 15. The cushion or yielding layer 17 is for the purpose of relieving the strain upon the lip plate 7 when twisted slightly under adjustment.

The channel beam 15 forms a rigid transverse support extending entirely across the machine between the sides or pond plates 6a and is hinged in the rear at 16 to the main transverse frame 33 forming an integral structure with the sides or pond plates.

A rock shaft 21 is suitably journaled in relatively fixed bearings and is provided with one or more eccentrics 20 positioned in

a slot between the two arms 25 forming an integral structure with the transverse channel beam 15. The rock shaft 21 is provided with a segment of a worm wheel 22 with which meshes a worm 23, arranged to be rotated by a hand wheel and shaft 24. By this means, the rock shaft 21 may be rotated in one direction or the other, as may be necessary and is, in effect, locked in any desired position of adjustment. It will be understood that when the worm and worm wheel are rotated, the eccentric 20 is also rotated and moves the channel beam 15 and the parts connected to it, about the hinge 16. 10 This adjustment will lower or raise the channel beam 15 and with it the flexible lip plate 7 toward or from the front end of the bottom plate 6, with the result that the nozzle 5 of the slice is varied in height simultaneously across the entire machine.

25 A transversely arranged angle bar 28a is rigidly attached to move with the oscillatory movements of the channel beam 15 and the lip plate 7. Secured to the forward face of this angle bar 28a and in spaced relation are a series of adjusting devices for adjusting the upper flexible lip of the lip plate 7 in the manner heretofore described.

30 I will now describe the details of the adjusting means for the upper lip of the slice nozzle; and as all of these means are alike, it will suffice to describe one of them in detail.

35 Each device has a tubular body part 26 bolted to the face of the angle bar 28a. A tubular bushing 26a snugly fits the tubular bore of the body part 26 and is screw threaded at its upper end which is received within the threaded interior of a nut lock 28. The tubular bushing is provided with a milled head 29 by which it may be rotated when not prevented by the lock nut. 27 is a screw threaded shaft which extends entirely through the tubular bushing and at its lower end it is hinged at 32 to the locknut 30 whose 40 lower end is hinged at 31 to the upper side of the flexible lip 7 of the slice.

45 It will now be understood that by releasing the pressure of the locknut upon the upper part of the tubular bushing 26, the said bushing may be rotated upon the shaft 27 by rotating the head part 29 and in this way adjusting the screw threaded shaft 27 in a vertical direction. The lock nut portion 28 is adjusted to definitely hold the tubular bushing 26 without any further rotation. Each one of the adjusting portions is of the same capacity and it is evident that the adjacent portions of the flexible lip 7 may be also adjusted (to the various speeds) either in the same direction or in opposite directions, for varying the vertical position of the throat 5 transversely across the machine.

50 When the adjustment is determined to be just what is to be desired, the entire throat across the machine may be simultaneously

increased or decreased by the manipulation of the hand wheel 24.

The head box 11 supplies the paper stock to the throat 8 under a static head equal to the height of the fluid in the upright passage 10 above the slice nozzle 5, and this static head may be increased or decreased by adjustment of the dam or baffle plate 12 over which the paper stock flows. This plate 12 is guided in vertical guideways and is moved by a pinion 14 meshing with a rack 13 secured to the plate.

55 The throat 8 gradually decreases in area and reaches a minimum at the slice nozzle 5. By this construction the velocity of the pulp fluid mixture is caused to gradually increase in velocity reaching its maximum at the slice nozzle 5 and this velocity or speed of flow through the throat may be regulated by varying the static head in the chamber 10 by manipulation of the dam or baffle plate 12. The throat 8 and passage 10 are in the form of a sinuous or reverse curve, being vertical at its large or static head end and substantially horizontal at its orifice or nozzle end where it delivers to the wire 2, and said form provides normally a substantially constant head and a gradually changing in direction of flow to a maximum with the least disturbance of the pulp. The result of this is that 85 a very uniform thickness or weight of the paper is assured.

60 The jet of paper stock, as it emerges from the nozzle 5, is maintained of the proper vertical thickness by the adjusting devices 26 as before explained, which operate to position the lip 7 nearer to or further from the plate 6 and wire 2 for regulating the stock flow at various spaced points across the machine and whereby an even thickness of pulp sheet is formed on the wire.

65 As a further refinement, I prefer to employ vertical rectifier plates 9 arranged parallel across the throat 8, said plates being supported from the lower wall of the throat and sufficiently narrow as not to obstruct the free flow of the fluid. The object of these rectifier plates is for straightening out any small cross currents or disturbances in the fluid flow which may occur and thereby obtain a straight flow from nozzle 5.

70 The main transverse frame 33 as a whole is vertically adjustable and by means of a lifting jack 35 may be lifted at times of changing the wire about the breast roll 4. At other times this frame 33 is lowered to the position shown and forms liquid tight joints at 36 to prevent undue leakage of the paper stock from the throat.

75 For convenience of the operator in making adjustments a footway 39 may be provided transversely across the machine above the slice. Also, a tube gauge 38 may be employed opening into the throat at 37 for showing 130

the actual head of pulp being employed while the machine is running.

It will now be apparent that I have devised a novel and useful construction which embodies the features of advantage enumerated as desirable, and while I have in the present instance shown and described the preferred embodiment thereof which has been found in practice to give satisfactory and reliable results, it is to be understood that I do not restrict myself to details, as the same are susceptible of modification in various particulars without departing from the spirit and scope of the invention.

Having now described my invention, what I claim is new and desire to secure by Letters Patent, is:

1. A slice for paper making machines comprising a throat terminating in a nozzle, the upper lip of which is flexible, combined with a plurality of adjusting means arranged at spaced intervals across the machine for separately adjusting the nozzle lip to provide capacity for varying the vertical size of the nozzle orifice and fluid jet delivered therefrom and wherein further, the throat is made tapering in cross sectional area along its length and means constituting a static head within the throat are provided at its largest end for adjusting the static head to provide regulable initial velocity pressure.

2. A slice for paper making machines comprising a throat terminating in a nozzle, the upper lip of which is flexible, combined with a plurality of adjusting means arranged at spaced intervals across the machine for separately adjusting the nozzle lip to provide capacity for varying the vertical size of the nozzle orifice and fluid jet delivered therefrom and wherein further, the throat is divided transversely near its nozzle made tapering and provided near its nozzle end with parallel rectifier plates in the nozzle end to straighten out cross currents which may be present in the flowing pulp to insure uniform pulp delivery.

3. The combination of a slice having an orifice and a tapered throat communicating with the orifice, and a plurality of vertical parallel rectifier plates in the throat and extending across the slice for straightening out cross currents which may be present in the flowing pulp, and means for maintaining a static head to the flowing pulp above the level of the slice orifice, said means adjustable to vary the static head and thereby the velocity of the pulp flow from the orifice.

4. A slice for paper making machines comprising a throat terminating in a nozzle, the upper lip of which is flexible, combined with a plurality of adjusting means arranged at spaced intervals across the machine for separately adjusting the nozzle lip to provide capacity for varying the vertical size of the nozzle orifice and fluid jet delivered there-

from and wherein further, means are provided for bodily lifting the slice clear of the wire of the paper making machine without disturbing the relative adjustments of the plurality of adjusting means of the nozzle and lip thereof.

In testimony of which invention, I hereunto set my hand.

RALPH WOOD.
